UNITED STATES PATENT OFFICE

JOSEPH JOHN NELIS, OF BROOKLYN, NEW YORK, ASSIGNOR TO FOSTER WHEELER CORPORATION, OF NEW YORK, N. Y., A CORPORATION OF NEW YORK

STEAM GENERATOR

Application filed April 16, 1928. Serial No. 270,205.

The general object of the present invention is to provide a steam generator characterized by features of construction and arrangement whereby the generator is adapted for use in 5 efficiently generating steam at high pressures and giving the steam generated a high degree of superheat while keeping the required head room lower than has been the case with previous steam boilers capable of the same 10 steaming capacity and other operating characteristics of the new steam generator and in which the center of gravity of the generator is at an appreciably lower level than in previous generators adapted for such use and also 15 requiring no more head room.

The invention is characterized by the arrangement of the water heating surface of the generator in the form of a bank of so-called horizontal tubes; that is, tubes inclined at a 20 relatively small angle to the horizontal and connected at their ends to a lower water drum and to an upper steam and water drum, and the combination of this water heating surface with a radiant heat superheater which 25 unites with the bank of water tubes to form a heat absorbing roof for all, or practically all of the length of a horizontally elongated combustion chamber and combined with a contra flow economizer located above the bank 30 of water tubes and having its top portion at approximately the same level as the top of the steam and water drum.

My improved steam generator was especially devised for and is especially adapted for 35 use in Mississippi River type towboats and like shallow draft river craft and to fit in the space heretofore commonly occupied in such vessels by the return tubular boilers heretofore in general use in such craft. My im- 40 proved steam generator adapted for such use can be readily operated as to give as good a thermal efficiency as is characteristic of good modern central station practice in which the efficiencies regularly attained are fully double 45 those commonly attained with the return tubular boiler units which my improved steam generator is devised and adapted to replace.

My improved steam generator because of 50 the character, and particularly because of the

simplicity of its construction, is well adapted for use with steam pressures as high as are now considered desirable for any service, that is, the generator may be constructed for steam pressures running from 200 pounds up to 1000 55 or 1200 pounds per square inch. The described superheating provisions permit of the ready attainment of such a substantial superheat as 100° or upward. The construction permits of the use of an economizer without 60 infringement on the space requirements effective to reduce the temperature of the heating gases discharged to 300° F. or less and thus contributes materially to the efficiency 65 obtained.

The improved steam generator is characterized by a horizontally elongated combustion chamber, the volume of which is much greater than, about four-fold, that of the above mentioned return tubular boiler units, 70 and this increased volume of combustion chamber space and the other advantages referred to are obtained in my improved steam generator with its center of gravity at a substantially lower level than is the case with 75 such a return tubular boiler as is referred to above of similar capacity and requiring the same over-all head room. This lowering of the center of gravity is of especial importance in the case of shallow river craft which are always top heavy and for that reason not infrequently capsize when struck by relatively 80 moderate wind squalls. The generator is also characterized by having approximately half the weight of existing types of marine 85 boilers. While my improved steam generator may be fired in any usual or suitable manner, it is to be noted that the heat absorbing roof of the combustion chamber is of especial utility where the generator is heated 90 by the combustion of powdered coal or oil.

The various features of novelty which characterize my invention are pointed out with particularity in the claims annexed to and 95 forming a part of this specification. For a better understanding of the invention, however, and the advantages possessed by it reference should be had to the accompanying 100 drawings and descriptive matter in which I

have illustrated and described a preferred embodiment of the invention.

Of the drawings:

Fig. 1 is an elevation in section; and

Fig. 2 is a front elevation of my improved boiler.

In the drawings I have illustrated a preferred embodiment of my invention in which a steam generator A having vertical front and side walls A' and A², respectively, is provided with a horizontally elongated combustion chamber having a front section B' and a rear section B², partially separated by a bridge wall A³. A steam and water drum C, mounted transversely above the rear portion of the chamber section B' is connected to a lower transverse water drum D, supported externally of the combustion chamber section B². The drums are connected by a bank of horizontally inclined water tubes E. The drum D is supported on a casting D' located on the boiler room floor behind the lower part of the generator rear wall A⁴, which is cut away to partially support the drum. Each of the water tubes E enters the drums C and D radially as shown in Fig. 1.

A curved intertube baffle F, supported on and cooled by the lower tubes of the bank, extends from the bottom of the steam and water drum downwardly towards the water drum D. An upper baffle G, mounted on and cooled by the uppermost row of water tubes E, extends from the rear wall of the boiler housing upwardly toward the steam and water drum C. The baffle G is substantially parallel with the major portion of the baffle F.

An economizer H preferably of the contra flow type comprising a horizontal casing H' containing a plurality of horizontal gilled tubes H² in staggered relation is mounted above the baffle G. The gas inlet end of the economizer is in vertical alignment with the upper end of the baffle G. The generator rear wall continues upwardly from the top of the water drum D to the bottom of the economizer H and connects thereto adjacent the economizer exit end. In some cases the baffle G may be advantageously eliminated and the bottom of the economizer used as the upper limit of the gas passage. This portion of the rear wall is provided with a removable panel A⁵ permitting inspection and repairs to the rear end of the boiler. The top of the economizer casing H' is approximately level with the top of the steam and water drum C and connected to the side of the drum by an inclined wall J.

The steam and water drum C is provided at its front side with a pipe inlet connection C' from the economizer water outlet (not shown). The pipe C' is connected to the drum at a point below a horizontal baffle C² extending longitudinally of the drum. The baffle C² is supported from the front side of the drum and extends transversely beyond

the vertical center line of the drum. A steam outlet connection C³ is mounted in the front side of the drum C slightly above the baffle C². Water gage connections C⁴ are shown at one end of the drum and a safety valve C⁵ at the front side.

The upper end of the generator front wall A' is connected to the lower part of the drum C by a horizontal roof portion having a radiant heat superheater K forming the underside thereof. The superheater K is composed of two sets of side by side forged steel tubes K' rectangular in cross-section extending transversely of the combustion chamber section B' and having enlarged end portions K² mounted on the side walls A². The superheater tube end portions of the section adjacent the water tubes E are connected to external headers L and M by nipples L' and M', respectively, while the superheater tubes of the section adjacent the front end of the boiler are connected to the header M at one end and to an inlet header N adjacent the header L. The header N is connected to the steam outlet C³ of the drum C by a pipe N'. The steam thus passes from the drum C to the header N, through the front superheater section to the header M from which it returns through the rear superheater section to the superheater steam outlet header L.

The steam generator shown can be fired with solid, liquid, powdered or gaseous fuel, although I have shown it as using solid fuel with a shaking grate P located in the lower part of the combustion chamber section B' and extending between the front wall A' and the bridge wall A³ of the boiler. Firing doors P' and ash doors P² are located in the lower part of the front wall above and below the grate respectively.

Soot blower tubes R are located at various points above the inclined bank of water tubes and among the economizer tubes. One of such tubes is positioned in a recess G' formed by a portion of the baffle G. An inspection door S is arranged in the upper part of the boiler side wall adjacent the heating gas inlet to the economizer.

In the boiler construction shown, the burning combustion gases pass upwardly from the grate P through the chamber section B'. The gases are directed by the bridge wall up to the tubes and by the baffle F down along and in intimate contact with the lower parts of water tubes E through the combustion chamber section B² and pass around the lower end of the baffle F into the gas passage formed by the baffles F and G. The heating gases then pass upwardly among the upper rows of water tubes into the economizer H, from which the gases pass directly or indirectly to the stack. The superheater and the upper ends of the lower rows of water tubes absorb heat by radiation from the burning gases and the surrounding wall surfaces. The wa-

ter tubes also absorb heat by convection and conduction from the heated gases contacting therewith.

The circulation of water in the tube bank is downward through the upper rows of tubes to the drum D and upwardly through the tubes in front of the baffle F. My invention is not restricted to the specific water circulation described and the drum connections may be so arranged that the flow is upwards through all of said tubes if desired. The steam passing out of the upper ends of the tubes carries along slugs of water which are discharged against the baffle C² and prevented by the baffle from passing directly to the superheater. This arrangement of the baffle C² separates the drum C into a lower water chamber and an upper steam chamber. The steam passes out through the connection N' to the superheater.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention what I claim as new and desire to secure by Letters Patent, is:—

1. A steam generator of a type having a low center of gravity and requiring only limited head room, and comprising an upper transverse steam and water drum, a lower transverse water drum a substantial distance rearwardly thereof and connected thereto by a plurality of horizontally inclined water tubes, a combustion chamber projecting in front of the steam and water drum and extending rearwardly therefrom to a point adjacent said lower water drum, an inclined baffle extending rearwardly between the tubes from the steam and water drum, a second inclined baffle extending forwardly immediately above the uppermost water tubes, said baffles overlapping each other and providing a lower rearwardly and downwardly extending gas pass and an upper forwardly and upwardly extending gas pass, an economizer comprising a plurality of transversely extending water tubes positioned above said second baffle and arranged to receive gases passing out of the forward end of said upper gas pass, the overall height of the generator at said economizer being substantially the same as at said steam and water drum, a baffle extending horizontally in said steam and water drum above the points of connection of said water tubes to said drum, feed water conduits connecting the forward tubes of said economizer to said steam and water drum be-

low said drum baffle, and a steam outlet connection from said steam and water drum above said drum baffle.

2. A steam generator of a type having a low center of gravity and requiring only limited head room, and comprising an upper transverse steam and water drum, a lower transverse water drum a substantial distance rearwardly thereof and connected thereto by a plurality of horizontally inclined water tubes, a combustion chamber projecting in front of the steam and water drum and extending rearwardly therefrom to a point adjacent said lower water drum, an inclined baffle extending rearwardly between the tubes from the steam and water drum, a second inclined baffle extending forwardly immediately above the uppermost water tubes, said baffles overlapping each other and providing a lower rearwardly and downwardly extending gas pass and an upper forwardly and upwardly extending gas pass, an economizer comprising a plurality of transversely extending water tubes positioned above said second baffle and arranged to receive gases passing out of the forward end of said upper gas pass, the overall height of the generator at said economizer being substantially the same as at said steam and water drum, a baffle extending horizontally in said steam and water drum above the points of connection of said water tubes to said drum, a feed water conduit connecting a forward tube of said economizer to said steam and water drum below said drum baffle, a horizontal roof portion for said combustion chamber portion in front of said steam and water drum, a radiant heat superheater having a plurality of steam conduit elements lining said horizontal roof portion, and a steam conduit connection from said steam and water drum above said drum baffle to said superheater.

Signed at New York city, in the county of New York and State of New York this 12th day of April, A. D. 1928.
